FIG. 2

INVENTOR

Nicholas J. Egler
By Kayette Brown
aetp

UNITED STATES PATENT OFFICE.

NICHOLAS F. EGLER, OF CHICAGO, ILLINOIS.

REVERSING-VALVE MECHANISM.

Application filed June 1, 1923. Serial No. 642,780.

To all whom it may concern:

Be it known that I, NICHOLAS F. EGLER, a citizen of the United States, and resident of Chicago, in the county of Cook and State 5 of Illinois, have invented a new and useful Improvement in Reversing-Valve Mechanism, and I do hereby declare the following to be a full, clear, and exact description thereof.

10 My invention relates to a reversing valve mechanism for use in connection with open-hearth or like furnaces.

Heretofore it has been generally customary to employ a pair of valves usually of 15 the mush-room type, the valves being so arranged that when one is open the other is closed. The open valve is in the direct line of the hot gases, and is subjected to an intense heat which reduces the life of the 20 valve and makes repairs and substitutions of frequent occurrence.

The object of my invention is to provide a construction in which a single valve is employed covering only one flue at a time, the 25 said valve being always in closed position and low down in its seat, so that it is not in the direct path of the hot gases, consequently is not subjected to the wear and tear caused by the intense heat.

30 In the accompanying drawing, Fig. 1 is a vertical elevation of a portion of a suitable furnace showing my invention applied thereto; and Fig. 2 is a section on the line 2—2, Fig. 1.

35 In the drawings the numeral 2 designates the gas inlet flue, 3 the stack-flue and 4 the furnace-flue. A hood or box A is provided for covering the above-designated flues, and by means of which the reversing of the gas or 40 air and the waste gases is accomplished under a single hood or box.

The reversing valve 5 is preferably of a low flat construction, and may be water-cooled as illustrated, or if desired may be 45 formed of a highly refractory material. The valve is provided with the flaring portion 6 which is adapted to enter one of the water-seal wells 7 surrounding the flues 2 and 3.

50 Where the water-cooled valve is employed a flexible pipe 8 is employed which permits of the movement of the valve from one flue to the other as will more fully hereinafter appear. The pipe 8 is connected up to any 55 suitable source of supply.

The valve 5 is provided with the lugs 9

which are provided with recesses 10 to receive the up-turned arms 11 of the yokes 12. The other arms 13 of the yokes carry the rollers 14 which are adapted to travel 60 on the arc-shaped tracks 15.

To provide for the shifting of the valve from one flue to another, levers 16 are employed, said levers being connected at their inner ends to the rock shaft 17 mounted in 65 bearings 18. The levers 16 are also connected at 19 to the yokes 12. A handle 20 is connected to one of the levers 16, so that by the movement of said handle the levers and yokes will be operated simultaneously. 70

I provide a counter-balance to aid in the ease of the operation of the movement of the valve, and accordingly a chain 21 is connected to the valve handle 29, said chain passing between the sheaves 22, thence over 75 the sheaves 23 and 24, the weight 25 being connected to the outer end of said chain.

A suitable door 26 is provided for access to the valve.

In order to keep the parts of the apparatus cool, the water-box 27 is provided, and with the water level maintained as at 28 the cooling of the working parts is assured.

When the valve is in the position shown 80 in Fig. 1 and it is desired to shift it to close the stack-flue 3, the levers 16 are thrown over to the position indicated in dotted lines, Fig. 1 and by this movement the valve 5 will be raised and the rollers 14 85 90 will move over the arc-shaped tracks 15, whereupon the valve is lowered into the water-seal 7 surrounding the stack-flue 3, as clearly shown in dotted lines, Fig. 1.

Referring to Fig. 1, the connection at 19 95 between the levers 16 and the valve 5 is slightly to the right of the center of gravity of the valve, so that the rollers 14 will carry a portion of the weight of the valve. By this arrangement the levers 16 carry most 100 of the weight of the valve when it is being shifted, but sufficient weight is imposed upon the rollers 14 so that they will serve, together with the track 15, to guide the valve 5 in such manner that it is maintained in a substantially horizontal position thus preventing tilting thereof and facilitating its movement from one flue to the other. 105

When the valve is in the position indicated in Fig. 1, in closing the gas-flue it is 110 only subjected to the cool gas and consequently is not highly heated, and when mov-

- ed to close the stack-flue it is low down and out of the direct path of the hot gases, and consequently is not exposed to the intense heat which would be the case were the valve suspended at a point above the flue as in the case where pairs of valves are employed so that when one is raised the other is lowered. As the hood A covers the gas or air flue, one waste gas flue to the stack, and one flue 10 from the valve to the furnace, known as the furnace flue, the said hood is filled with gas or air at one period, and with waste gas at another period, which makes it a three-flue reversing valve.
- 15 By the use of a single valve of a low flat type, I greatly prolong the life of the valve, and at the same time reduce the cost of original construction by making one valve take the place of two.
- 20 It will of course be understood by those skilled in the art that what is illustrated in Figs. 1 and 2 is only one-half the equipment for each furnace, and that the above described parts will be duplicated to make a 25 complete equipment for each furnace.
- What I claim is:
1. In valve reversing mechanism for furnaces, the combination of a hood covering three distinct flues, a single valve covering 30 a single flue, and means for shifting said valve from the gas or air flue to the stack flue, and vice-versa.

2. In valve reversing mechanism for furnaces, the combination of a hood covering three distinct flues, a single low flat valve 35 covering a single flue, and means for shifting the said valve from the gas or air flue to the stack flue, and vice-versa.

3. In valve reversing mechanism, the combination with a cover member, of levers connected to opposite sides of said cover member, at points offset with respect to a transverse center line of gravity of said cover member, a roller carried by said cover member, and an arcuate track with which said 40 roller may co-operate to support a portion of the weight of said cover and guide the same when said levers are being shifted to move said cover.

4. In valve reversing mechanism for furnaces, the combination with a shiftable valve member, of a lever pivotally supported at one end and connected to said valve member at a point offset with respect to the center of gravity thereof, a pair of rollers connected to said valve member and adapted to support a portion of the weight thereof, and a track of arcuate form with which said 55 rollers co-operate to partially support and guide said valve member when it is being shifted by movement of said lever.

In testimony whereof I, the said NICHOLAS F. EGLER, have hereunto set my hand.

NICHOLAS F. EGLER.
